UNITED STATES PATENT OFFICE

GUSTAF ADOLF JUHLIN, OF TIMPERLEY, ENGLAND, ASSIGNOR TO GENERAL ELECTRIC COMPANY, A CORPORATION OF NEW YORK

ELECTRIC CIRCUIT INTERRUPTER

Application filed November 19, 1931, Serial No. 576,163, and in Great Britain December 16, 1930.

This invention relates to electric circuit interrupters of the expulsion type in which the contacts are immersed in oil or other insulating liquid and separate within an arc-
3 ing chamber or "explosion pot".

A principal object of this invention is the provision of an improved circuit interrupter of the above expulsion or "oil-blast" type which shall be simple and rugged in construc-
10 tion and positive and efficient in operation.

In accordance with the present invention one or more channels transversely positioned with respect to the arc drawn between the contacts communicate with the arcing chamber or explosion pot indirectly through a second or auxiliary chamber which is arranged to provide a reserve supply of oil adequate for quenching the arc. Preferably, the arcing chamber or explosion pot is of
20 comparatively small dimensions and is constructed integrally with the auxiliary chamber, the whole being immersed in the main body of oil contained in the oil tank in which other parts or other contacts of the circuit
25 interrupter are located. The moving contact is arranged to be moved upwards and downwards in a well known manner with respect to the fixed contact within the arcing chamber, for closing and opening the circuit
30 breaker, the insulating wall forming the base of the two chambers which communicate with one another adjacent the upper part thereof.

This invention will be more fully set forth in the following description, referring to the
35 accompanying drawing, and the features of novelty which characterize this invention will be pointed out with particularity in the claims annexed to and forming a part of this specification.

40 To enable the invention to be clearly understood it will now be described with reference to the accompanying drawing, of which Fig. 1 is an elevational view, partly in section, of a part of a circuit interrupter constructed in accordance with the present invention, and Figs. 2 and 3 are detailed plan views of circuit interrupter structure.

45 Referring to the drawing, and more particularly Fig. 1, the main arcing chamber is indicated at 1 in which is mounted the fixed

contact 2 of the circuit interrupter which may be of any suitable type. Preferably, however, contact 2 is of the well known resilient socket or self-aligning type. The movable contact indicated at 3 is of the plug type, 55 the contact 3 being carried in a well known manner upon a conducting bridge 4 at the other end of which may be a similar contact cooperating with a fixed contact in another arcing chamber (not shown). A part of the main oil tank containing insulating liquid in which the above structure is immersed is indicated at 5.

The main arcing chamber 1 is formed within a casing comprising a metal casting 5' having a cylindrical wall 6 preferably lined with a tube 7 of refractory insulating material, said arcing chamber being closed at its lower end by the insulating wall 8, which will be hereafter described. The upper portion of 65 the casting 5' is provided with connecting means, as 6', for supporting the explosion chamber structure and electrically connecting the contact 2 through the metal casting to the lead-in conductor 2'. A portion of the 70 wall 6 comprises a partition likewise forming within the casing an auxiliary chamber or oil reservoir 9 which communicates with the main chamber 1 by the opening 10 adjacent the top of the two chambers. 75

The insulating wall 8 closes the lower ends of both chambers 1 and 9 and has a main passage 11 through which the plug contact 3 is moved for closing and opening the circuit, said passage 11 providing a reasonable 80 clearance for the contact, the passageway being most narrow at the base of the wall 8, as indicated at 12. The insulating wall 8 is also provided with a plurality of trans- 85 verse channels, three being shown in Fig. 1, said channels being indicated at 13. The channels 13 extend across the passage 11— 12 through which the arc is drawn during opening of the circuit and open at the left 90 into the main oil tank 5 and at the right into the vertical exhaust duct 14, which communicates with the oil reservoir chamber 9. 95

The insulating wall 8 in which the passage 11—12 and the channels 13 and duct 14 are formed is conveniently constructed of a 100

plurality of plates. Three plates 15, one of which is shown separately in plan in Fig. 2, two plates 16, one of which is shown separately in Fig. 3, and a base or cover plate 17 are stacked as hereinafter described to complete the structure.

Each plate 15 (Fig. 2) has a perforation 11 through which the plug contact 3 moves, and an arcuate perforation 14. Each plate 16 (Fig. 3) has an opening 18 which is conveniently of the shape shown, said opening having a portion at the right which corresponds with the perforation 14 in each of the plates 15, a central narrow portion through 15 which the moving contact 3 passes and a flared mouth through which the streams of oil emerge into the main oil tank. The plates 15 and 16 and also the plate 17 are provided with holes 19 to enable the several 20 plates 15, 16 and 17 to be bolted or secured together in any suitable manner, as by six bolts, three of which are indicated in dotted lines at 20 in Fig. 1. In some cases each channel 13 may be divided on the right side 25 of the main passageway 11 as by the provision of insulating washers 21 surrounding and located by an insulating peg 22 the ends of which are engaged in recesses in the upper plate 15 and the lowermost or cover plate 30 17, as shown.

By reason of the auxiliary chamber 9 it will be noted that the latter will contain a relatively large body of oil which is forced across the moving contact when the circuit 35 breaker is opened, due to the pressure caused by the arc which is formed in the arcing chamber 1, so that the arcing chamber may be made of desirably small dimensions.

A particular advantage of the above arrangement resides in the fact that the highly ionized and hot conducting gases generated by the arc are not readily mixed with the comparatively cool oil which is forced from the auxiliary chamber 9 and blasted 40 in separate jets transversely of the arc stream. The gas generated within the main arcing chamber 1, while subjecting the oil in the auxiliary chamber 9 to high pressure, is not afforded opportunity to mix with the 45 oil blast until the oil is practically exhausted from the chamber 9. However, in practice the arc is generally extinguished within a very short time at a current zero, during the initial part of the oil blast through the 50 transverse passages 13 so that exhaustion of oil from the chamber 19 before circuit interruption is unlikely. It will be apparent, of course, that the oil capacity of the auxiliary chamber 9 may be chosen in accordance 55 with the current interrupting characteristics involved so that there will be an adequate reserve of comparatively cool and fresh oil having high dielectric strength for the oil blast. By arranging the opening 60 65 at the upper part of the communicating arc-

ing and auxiliary chambers, the oil within the auxiliary chamber 9 is subjected to full pressure while minimizing any tendency for hot arc gases from the arcing chamber to mingle therewith.

It should be understood that this invention is not limited to specific details of construction and arrangement thereof herein illustrated, and that changes and modifications may occur to one skilled in the art 70 without departing from the spirit of this invention.

What I claim as new and desire to secure by Letters Patent of the United States is:

1. An electric circuit interrupter of the 80 oil-blast type comprising an arcing chamber, contacts separable in an insulating liquid within said chamber, an auxiliary chamber communicating with said arcing chamber containing insulating liquid in amount sufficient to interrupt the circuit, the liquid in said auxiliary chamber being subjected to pressure generated within said arcing chamber and means directing insulating liquid 85 under influence of said pressure from said auxiliary chamber across the arc formed between said contacts.

2. An electric circuit interrupter comprising explosion chamber structure immersed 90 in an insulating liquid including an arcing chamber and an auxiliary chamber containing insulating liquid in amount sufficient to interrupt the circuit, contacts separable within said arcing chamber arranged so that pressure is generated within said chamber 100 by arcing, and means communicating pressure from said arcing chamber to said auxiliary chamber effecting a blast of insulating liquid from said auxiliary chamber across the arc formed between said contacts.

3. An electric circuit interrupter of the oil-blast type comprising an arcing chamber, contacts separable in an insulating liquid within said chamber, an auxiliary chamber containing insulating liquid, said chambers 110 communicating adjacent the upper parts thereof so that liquid within said auxiliary chamber is subjected to the pressures generated within said arcing chamber, and means directing insulating liquid from the lower part of said auxiliary chamber across 115 the arc formed between said contacts.

4. In an electric circuit interrupter of the oil-blast type, explosion chamber structure comprising a casing having a partition dividing the same into an arcing chamber and an auxiliary chamber, said partition having an opening adjacent the top permitting communication between said chambers, insulating liquid filling said chambers, contacts separable within said arcing chamber, and insulating plates forming with said casing a 120 passage leading from the lower part of said auxiliary chamber communicating with a plurality of passages extending transversely of 125

the arc drawn between said contacts, said arc generating pressure within said arcing chamber causing a blast of insulating liquid from said auxiliary chamber through said trans-
5 verse passages and across the arc interrupting the circuit.

5. An electric circuit interrupter of the oil-blast type comprising explosion chamber structure immersed in an insulating liquid,
10 contacts separable within said structure generating pressure, and means forming a plurality of passages directing blasts of insulating liquid from said structure transversely across the arc drawn between said
15 contacts including a plurality of stacked insulating plates, each of said plates having apertures in alinement forming a passage from said structure, and other apertures in alinement forming a passage through which
20 one of said contacts may move, alternate plates forming apertures exhausting from said first-named passage to the exterior of said structure transversely of the arc drawn between said contacts.

25 In witness whereof, I have hereunto set my hand.

GUSTAF ADOLF JUHLIN.
